UNITED STATES PATENT OFFICE.

HENRY L. MILLER, OF KNOXVILLE, TENNESSEE.

TROLLEY-WIRE SUPPORT.

1,389,773.

Specification of Letters Patent.

Patented Sept. 6, 1921.

Application filed December 5, 1919. Serial No. 342,618.

To all whom it may concern:

Be it known that I, HENRY L. MILLER, a citizen of the United States, residing at Knoxville, in the county of Knox and State 5 of Tennessee, have invented a new and useful Improvement in Trolley-Wire Supports, of which the following is a specification, reference being had to the accompanying drawing.

10 My improvement relates particularly to supports for trolley wires used in mines and similar situations.

The object of the invention is to provide a support the parts of which may be cast 15 and finished with a minimum amount of machine work and which shall be so formed as to adapt them for ready and accurate adjustment upon each other and upon the trolley wire.

20 In the accompanying drawings,

Figure 1 is a side elevation of a trolley wire support embodying my improvement;

Fig. 2 is a view of the same support looking toward the right as shown in Fig. 1;

25 Fig. 3 is an upright section on the line, 3—3, of Fig. 1, looking toward the right;

Fig. 4 is a perspective view of the two clamping jaws separated from the upper member of the support;

30 Fig. 5 is a top view of the jaws shown in Fig. 4, the jaws being separated from each other;

Fig. 6 is an elevation showing the inner 35 face of the fixed jaw;

Fig. 7 is an elevation showing the inner face of the adjustable jaw.

Referring to said drawings, A is the upper member of the support. This is of ordinary form and adapted to be secured 40 to a ceiling or the lower face of a horizontal timber. Said member comprises a downward-directed exteriorly screw threaded metal neck, A¹, which is embedded in non-conducting material, A², and surrounded 45 by a metallic washer, A³, resting against the lower face of the insulation material.

Below the member, A, are two jaws, B and C. The jaw, B, is immovably secured to the neck, A¹, and the jaw, C, is adjustably secured to the jaw, B, and the lower parts of the two jaws engage the trolley wire, E.

The two jaws nearly meet in an upright plane in which lies the axis of the neck, 55 A¹, and the axis of the trolley wire, E. The

lower part of each jaw is extended laterally along the trolley wire to extend the surfaces which engage the wire. Along the inner face of the jaw, B, is a horizontal groove, B¹, adapted to receive a portion of the trolley wire. The jaw, C, has on its inner face a corresponding groove, C¹, to receive a part of the trolley wire. At its upper end, the jaw, B, has a lateral extension, B², reaching across the above-mentioned upright plane. Said extension makes room for forming an upright aperture, B³, on the axial line of the neck, A¹. Said aperture is of proper diameter and is interiorly screw threaded to allow the jaw to be screwed on the neck. The upper end of the jaw, B, including the extension, B², is made flat and horizontal to adapt it to bear flatwise against the washer, A³. When this jaw has been turned to raise it as far as said washer 75 will permit, the jaw is immovable. The exposed lateral face of the extension, B², is made a part of the surface of a sphere having its center in the axial line of the neck, A¹.

On the inner face of the upper part of the jaw, C, is a recess or semi-socket, C², conforming in reverse to the rounded or spherical face of the extension, B². The extension, B², rests in said recess or socket. Thus 85 a semi-ball and socket joint is formed for the partial rotation of the jaw, C, in every direction.

A binding bolt, D, extends horizontally through apertures, D¹, formed in the jaws, B and C, a little way below the extension, B², and the socket, C². When said bolt is tightened the inner face of the socket, C², of the jaw, C, is pressed against the extension, B², and the lower edge of the jaw, C, 95 is pressed firmly against the wire, E, whereby said wire is pressed into the groove, B¹, of the jaw, B.

The apertures, D¹, are made larger than the diameter of the bolt, D, in order that 100 the bolt may be allowed adjustment in either of said apertures so as to give the jaw, C, freedom for adjustment in any direction that is possible for turning on the extension, B². Through such adjustment of the jaw, 105 C, a complete grip of the wire, E, between the two jaws may be effected, although mechanical inaccuracies may be present in both jaws. Among such inaccuracies may be warping or uneven shrinkage in the castings, 110

whereby the jaw, C, must turn in a special manner to cause the two jaws to fully grip the trolley wire.

I have found in practice that the two jaws 5 may be so cast as to require no more machining than the tapping of the aperture, B³, and in some cases the grinding of the upper end of the jaw B, and the cleaning of the grooves, B¹ and C¹.

10 For the placing of a trolley wire, the members, A, are secured in the desired positions. Then the jaws, B, are applied to the necks, A¹, until said jaws are rigid. Then each jaw, C, is applied loosely to the companion jaw, B. Then the wire, A, is strung along the line of supports and put into position between the jaws and in the jaw grooves of the supports. At each support, the bolt is tightened only sufficiently to keep 20 the wire from falling. Then the wire is adjusted endwise until it has been brought into its final position. Then the bolts are tightened to bring the jaws, C, into their final positions.

25 It is to be noted that the extension, B², on the jaw, B, constitutes the support for the jaw, C, the bolt, D, serving merely to draw the jaw, C, laterally, the jaw turning on the extension, B². The jaw, C, can not move 30 downward so long as the extension, B², is engaged in the socket, C². Furthermore, the bolt, D, is preferably made loose in the apertures, D¹, in order that the bolt may shift in said apertures sufficiently to allow 35 the jaw, C, to swing and turn on the extension, B², on the semi-universal joint.

I claim as my invention,

1. In a support of the nature described, 40 the combination of a pair of jaws having their lower edges adapted to grip a wire, and one of said jaws being formed for attachment to a superposed member and having a single lateral extension and the other jaw having a socket to receive said extension, 45 whereby a semi-universal joint is

formed, and means located below said extension and socket and acting horizontally, for drawing said jaws toward each other, substantially as described.

2. In a support of the nature described, 50 the combination of a pair of jaws having their lower edges adapted to grip a wire, and one of said jaws having a single lateral extension in which is an upright interiorly screw-threaded aperture and the other jaw having a socket to receive said extension, 55 whereby a semi-universal joint is formed, and means located below said extension and socket and acting horizontally for drawing said jaws toward each other, substantially 60 as described.

3. In a support of the nature described, 65 the combination of a pair of jaws having their lower edges adapted to grip a wire, and one of said jaws being formed for attachment to a superposed member and having a single lateral extension and the other jaw having a socket to receive said extension, 70 whereby a semi-universal joint is formed, and each of said jaws having a transverse aperture, and a binding bolt extending through the apertures, substantially 75 as described.

4. In a support of the nature described, 80 the combination of a pair of jaws having their lower edges adapted to grip a wire, and one of said jaws having a single lateral extension in which is an upright interiorly screw-threaded aperture and the other jaw having a socket to receive said extension, 85 whereby a semi-universal joint is formed, and each of said jaws having a transverse aperture, and a binding bolt extending through the apertures, substantially as described.

In testimony whereof I have signed my name, this 3rd day of December, in the year one thousand nine hundred and nineteen.

HENRY L. MILLER.
